UNITED STATES PATENT OFFICE.

JAMES ALPHEUS GREEN, OF MILLDALE, VIRGINIA.

THILL-COUPING.

No. 818,437.

Specification of Letters Patent.

Patented April 24, 1906.

Application filed May 20, 1905. Serial No. 261,414.

To all whom it may concern:

Be it known that I, JAMES ALPHEUS GREEN, a citizen of the United States, residing at Milldale, in the county of Warren and State of Virginia, have invented certain new and useful Improvements in Thill-Couplings, of which the following is a specification.

This invention relates to thill-couplings, and is designed more particularly as an improvement on the device for which Letters Patent were granted to me October 1, 1901, No. 683,854, which consists of a thill-coupling for the ordinary clip, said coupling having an upper jaw and lower jaw arranged with such relation to each other as to admit of sufficient freedom of motion as to allow the lower jaw to close on a bolt of any size and prevent the rattling and automatically take up its own wear.

Generally considered, the present invention relates to a thill-coupling which will obviate the use of bushing or other type of packing and which will automatically take up wear and adapt itself to coupling-pins, bolts, and like fastenings varying in size, with the result that looseness of any kind is prevented and rattling wholly obviated.

With the objects aforesaid in view it is the purpose of the present invention to devise simple appliances for attaining the desired end and which will admit of the thills, pole, or like draft device being readily coupled to and uncoupled from the vehicle and which at the same time will admit of easy and ready manipulation of the parts when effecting the coupling and uncoupling, the coupling being entirely automatic.

In its organization the coupling comprises a thill-iron provided with a hook constituting a jaw and dog pivoted thereto and provided with a recess constituting a companion jaw for coöperation with the jaw of the thill-iron, a lock-lever fulcrumed to the thill-iron or other convenient portion of the thill or pole and adapted for coöperation with the pivoted dog to prevent displacement thereof after the coupling has once been effected, and a spring normally exerting a pressure upon the lock-lever to cause it to exert a pressure upon the pivoted dog, whereby wear is automatically taken up and the coupling is enabled to automatically adjust itself to variable fastenings applied to the axle or thill-clip.

For a full description of the invention and the merits thereof and also to acquire a knowledge of the details of construction of

the means for effecting the result reference is to be had to the following description and accompanying drawings, in which—

Figure 1 is a side view of a thill-coupling embodying the invention. Fig. 2 is a view similar to Fig. 1, showing the parts in section and illustrating the operation by dotted lines. Fig. 3 is a view of the coupling inverted, parts being broken away. 65

Within the purview of the invention the coupling, although particularly designed for the thills or shafts of vehicles, may be advantageously employed for attaching poles, surrey-shafts, and like draft devices to the various styles and types of vehicles or machines adapted to be drawn by animal power. 70

Inasmuch as the invention in its general adaptation is designed for vehicle-shafts, it is shown in this connection in the accompanying drawings, in which the thill or shaft is indicated at 1 and 2, the iron attached thereby to suitable fastenings, such as bolts 3. The thills 2 may be of any formation depending upon the special use of the coupling, and its outer or attaching end is recessed to provide a hook 4, the inner portion of the recess being adapted to receive the coupling-pin 5 or analogous fastenings coöoperating with the clip 6, by means of which the thill, 85 shaft, pole, or the like is attached to the vehicle to be drawn. It is to be understood in this connection that the thill-iron may be of integral construction, being preferably forged. 90

A dog 7 coöperates with the attaching end of the thill-iron and is pivoted thereto at a point between its ends, the pivot-fastening being indicated at 8. The outer end of the dog 7 is notched or recessed, as shown at 9, 95 to form a seat or jaw for reception of the coupling-pin or fastening 5. In the preferable construction the dog 7 is arranged between lugs 10, forming a part of the thill-iron and transversely spaced, so as to receive 100 between them said dog. The notched or gripping end of the dog 7 may be of any width, and in some instances it may be preferable to have it correspond with the width of the hook 4, so that the complementary jaws of the coupling will be flush at their outer sides. The dog 7 may be of any construction or shape so long as it serves, in connection with the hook 4, to firmly grip the fastening 5 and provide a substantial connection that will resist the strain and wear incident to devices of 105 this character. 110

The outer or gripping end of the dog is made rounding, so as to obtain a close fit against the inner side of the hook 4, thereby relieving the pivot connection 8 of the major 5 part of the strain incident to the use of the coupling. The tail portion of the dog is preferably tapered and is adapted to enter a seat formed upon the under side of the iron when the notched end of the dog is exposed, as 10 shown by the full lines in Fig. 2, thereby being out of the way and enabling the lock-lever to lie close to the thill-iron.

The lock-lever 11 is arranged beneath the thill-iron and is pivoted at a point between 15 its ends thereto, and its outer end is provided with a widened portion, forming a head 12, which is adapted to come in contact with the tail portion of the dog 7 and hold the latter in locked or closed position, as shown most 20 clearly in Fig. 1. The rear or handle end of the lock-lever is curved by preference and slightly tapered and is shaped to afford a convenient grip for the hand. Spaced lugs 13 project from the iron 2, and the lock-lever is 25 arranged between said lugs and pivotally connected thereto by means of a pin 14 or like fastening. The lugs 13 may occupy any position with reference to the iron and may be formed in any manner found most 30 convenient and economical in manufacture. It is to be understood in this connection that the configuration of the lugs 13 and the coupling end of the thill-iron will be such as to enable the article to be constructed or forged in 35 an economical and practical manner. It is also noted that the parts are to be so proportioned as to enable them to occupy a compact relation and yet be easy of manipulation. A projection 15 is formed upon the inner or top side of the handle end of the lock 40 adjacent to its pivotal support for coöperation with the spring 16, so as to prevent overstraining of the said spring when pressing upon the lock-lever to effect release of the 45 dog 7 when it is required to disconnect the thills, shafts, or the like from the vehicle.

It is essential in the operation of the coupling that a spring be provided to hold the lock-lever 11 in proper working position, so 50 as to prevent casual disengagement of the dog 7 when the invention is in operation and also to automatically take up wear and admit of the coupling adapting itself to different sizes of fastenings 5. This spring may be 55 of any construction, location, and outline and is preferably arranged so as to exert a pressure upon the lock-lever to force the handle end away from the thill-iron and the opposite end 12 toward said thill-iron and in contact with the dog 7. In the preferable construction a flat spring is employed and is interposed between the thill-iron and lock-lever 60 and may be attached positively to either one, as found most advantageous. In some instances the spring may be attached directly

to the handle end of the lock-lever and in other cases it may be fastened to the thill-iron, and, if desired, it may be so formed as to enable the lock-lever to be dispensed with, an end portion of the spring being extended 70 and shaped so as to coöperate with the dog 7 to hold it in locked position and projected beyond said dog to provide a finger-piece for convenience of operating the spring when it is required to release the dog from the coupling-pin or fastening 5 of the axle-clip. The spring may be attached to the thill and thill-iron by the same bolt or fastening employed for connecting these parts, or it may be secured solely to the thill-iron by being riveted or 80 otherwise fastened either to the base portion thereof or to the lugs 13, to which the lock-lever is fulcrumed. To increase the range or usefulness of the coupling and enable it to be used under all conditions and to meet every 85 requirement of the trade, it is contemplated to construct the parts with a view to enable the advantageous employment of the ordinary brace used in connection with light thills or shafts. This may necessitate varying the proportions and location of the lugs 13, and it is to be understood that such changes are contemplated within the purview of the invention. In this connection it is to be observed that the lugs 13 are to be 90 of such relative length as to admit of the brace passing between them and between the spring and main forging, so as to be secured by the same fastening or T-bolt 3 commonly employed for securing the rear end of the 95 thill to the forging or thill-iron.

The thill-coupling, as herein stated, is of such construction as to be automatical in operation, and when it is required to couple thills equipped with the invention to the clip-irons of a vehicle the dogs 7 are moved to occupy a position with their notched ends 9 exposed, so that when placing the thills in position the fastenings 5 will enter said seats 9 and a pressure upon the thill in a rearward and downward direction will cause the dogs to turn upon their pivot-supports 8 and carry said fastenings into the hook or space at the rear end of the thill-irons or forgings. This movement is effected against the tension of 105 the spring 16 and the action of the lock-lever, the head 12 of the latter riding upon the tail of the dog and snapping in the rear thereof after the coupling-pin or fastening 5 has reached the limit of its movement in entering 110 the jaw of the thill-iron. The parts are such that the lock-lever exerts a constant pressure upon the tail end of the dog to automatically take up wear between the jaws of the coupling and the coupling-pin or fastening, thereby preventing any possible rattling or appreciable play between the parts.

As the automatic trip in a thill-coupling cannot possibly be effected in any other style of dog or clutch except as herein shown, no 130

pivotal or other application of spring-pressure can alter the merits of this invention.

Therefore as supplemental to the parent patent I claim as my invention and desire to protect by Letters Patent—

1. In an automatic thill-coupling and in combination with the thill-iron or forging provided with an engaging jaw, a pivoted dog provided with a complementary jaw and having a tailpiece and a spring-actuated lock-lever arranged to make positive engagement with opposite faces of said tailpiece to hold the dog either open or closed.

2. In a thill-coupling, the combination of a thill-iron provided with an engaging end constituting a jaw, a dog coöoperating therewith and having a complementary jaw and oppositely-disposed cam-faces, and a spring-actuated lock device arranged to ride upon either cam-face and positively hold the said jaws either open or closed.

3. In a thill-coupling the combination of a thill-iron provided with an engaging end, a movable jaw coöoperating therewith, a lock-lever arranged to hold the movable jaw closed and to normally exert a pressure there-

on, and provided with a projection, and a spring normally exerting a pressure upon the lock-lever, and prevented from overstraining by means of said projection.

30

4. The herein-described thill-coupling comprising a thill-iron having its outer end recessed to form an engaging jaw and provided with spaced lugs a short distance from the rear of the jaw, a dog pivoted between its ends to the engaging end of the thill-iron and having a recess to form a companion jaw, a lock-lever pivoted between said spaced lugs and having its outer end widened to form a head for coöperation with the tail portion of the pivoted dog and having a projection upon its handle end and a spring interposed between the thill-iron and lock-lever and normally exerting a pressure upon the latter substantially as and for the purpose set forth.

35

In testimony whereof I affix my signature in presence of two witnesses.

JAMES ALPHEUS GREEN. [L. s.]
